APPARATUS FOR CLOSING CONTAINERS

Edward J. Stanek and Erich Malo, Milwaukee,
Wis., assignors to Stanek Tool & Mfg. Co.,
Milwaukee, Wis., a corporation of Wisconsin

Application April 24, 1933, Serial No. 667,600

1 Claim. (Cl. 226—85)

This invention relates to a method of closing a container by directly or indirectly supplying cement to the walls of the container adjacent the periphery of its opening and placing thereover a flat blank of sheet material, such as transparent cellulosic sheet material, in shape similar to the shape of the opening, but of greater extent so that the margin of the blank extends beyond the opening, and by then applying combined downwardly-axial and inwardly-directed-radial pressure to the margin of the blank to draw the same downwardly into contact with the cement about the opening and at the same time stretching the blank to smoothness over the opening and finally by applying simple inwardly-directed-radial pressure on the margins of the blank for a sufficient time to permit the cement to establish an effective bond and seal while the stretched condition of the blank is maintained.

The invention further relates to a form of apparatus for the accomplishment of the above steps, in which apparatus a carrier clasps the exterior of a resilient ring and forms therewith a unitary, resilient, lined ring. The internal dimensions of the lined ring are arranged to be slightly smaller than the external dimensions of the container opening which is to be closed. The resiliency of the lining is such that the lined ring may be forced over the container opening while imposing thereon a moderate axial and radial pressure. The unitary lined ring is associated with propelling means adapted to move the ring perpendicularly to the axis of the container into a position embracing the opening thereof and, as is sometimes necessary, to permit the lined ring to so dwell during a normal cement-setting interval before removal thereof is effected.

The closing of containers of the class here involved has heretofore been accomplished with preformed or partially preformed caps or capsules. A common example of this is the crown seal or ordinary bottle cap wherein a preformed cap is placed upon the bottle and clamped into engagement with a retaining bead by the application of radial pressure. Soft metal and gelatine caps have been squeezed in similar fashion into conformity with the configuration of the container mouth by various means designed to exert simple, radial pressure thereon. In all of these closures a preformed or partially preformed cap or capsule having cylindrical or conical side walls is employed.

In this invention, however, a flat blank of sheet material is formed into a cap and affixed to the container in a single operation and at the same

time a highly flexible blank may be employed, because provision for stretching the same to acceptable smoothness is included.

The method and apparatus of this invention is best described by referring to the accompanying drawings, wherein:

Fig. 1 is a side view of an apparatus for carrying on the method of this invention;

Fig. 2 is a perspective view of a container closed according to this invention;

Fig. 3 is a cross-section of a lined ring;

Fig. 4 is a cross-section of a lined ring showing the action in simultaneously drawing, stretching and sealing the blank; and,

Fig. 5 is a partial cross-section of the lined ring during a cement-setting interval.

In Fig. 1 a simple form of machine embodying this invention and adapted to carry on the method thereof is illustrated. The machine is provided with a conveyor 1 upon which containers 2 may be placed at intervals, either by hand or automatically. The containers are conveniently provided with cement adjacent the openings, prior to being placed on the conveyor. The conveyor 1 is capable of an intermittent lateral movement 20 in the direction of the arrow. Appropriately stationed at the side of and above the conveyor 1 is the sealing mechanism 4, which is provided with a reciprocating rod 5 mounted to move in guides 6 and bearing on its lower end press foot 7. The rod 5 is urged to a raised position by spring 10 acting upon a boss 11 which is rigidly secured to rod 5. One end of a rocker arm 8 bears upon the upper side of boss 11 and the other end of rocker arm 8 is operatively joined by means of an elongated opening with connecting rod 9, which in turn drops to an operable connection with a pivoted treadle 16. Beneath the press foot 7 are pivotally mounted hold-up clips 12 which are held normally against the stops 14 by springs 13 in the position shown in the drawings. The tips of the hold-up clips 12 engage the lined ring 3 and hold the same in the position shown in the drawings until press foot 7 forces the same downwardly into engagement with the top of the container 2.

Also stationed at the side of and above the conveyor 1 is the stripping mechanism 17, the same being spaced from the sealing mechanism an appropriate interval in the direction of travel of the conveyor. The stripping mechanism is provided with a stripper ring 18, which is joined by means of a spider 19 to push-rod 20, which in turn bears a rigidly attached boss 15 which makes contact with a rocker arm 21. The push-rod 20

moves in a stationary guide 22. A spring 23 normally urges the rod 20 to a raised position. Pivotally connected to the rocker arm 21 is the push-rod 24 which operably engages one arm of a bell 5 crank 26. The other arm of bell crank 26 bears an elongated opening for engagement with the upper end of connecting rod 9.

The intermittent movement of conveyor 1 is obtained by the action of treadle 16 upon bell 10 crank 27 through boss 25, which is rigidly attached to the rod 9. The bell crank 27 is connected to a link 28 which in turn is connected to a lever 29 which bears a spring-pressed pawl 30. The pawl 30 is arranged to engage a ratchet 31 15 and move the conveyor each time the treadle 16 is released.

The lined ring 3 is shown in detail in Figs. 3, 4 and 5. By referring to these figures it will be noted that the lined ring is composed of a carrier 31 which is conveniently formed of metal or other suitable, rigid material. The carrier 31 is provided with a flared ring 32 for engagement with clips 12, above referred to.

The upper internal diameter of the carrier 31 25 is conveniently made larger than the external diameter of the container to be closed and the lower internal diameter of the carrier 31 is conveniently made to correspond with the diameter of the flat blank 33. The lower margins of the carrier 31 may be provided with retaining projections 34 for holding the blank 33 in position. The interior of the carrier 31 is shaped to accommodate and clasp the resilient lining 35 which may conveniently be a tubular torus of rubber. 30 The internal diameter of the lining 35 is slightly smaller than the external diameter of the container opening to be closed.

In forming a closure according to this invention cement 36 is applied to the rim of the container 2, as indicated in Fig. 3, or, alternately, the cement may be applied to the corresponding margin of the blank 33. A lined ring 3 is then placed in position above the container 2, as shown in Fig. 3, with the blank 33 retained in position by the projections 34. The press foot 7 is then operated by the treadle 16 to cause the lined ring 3 to descend to the position shown in Fig. 4. While this step of the movement is taking place the lining 35 becomes deflected inwardly, at the same time exerting upon the margin of the blank 33 a radial as well as axial pressure, as indicated by the component arrows in Fig. 4. This action extends the blank 33 to almost perfect smoothness and draws the margin of the blank into sealed contact with the side walls of the container. Upon the completion of this movement the ring assumes the position shown in Fig. 5. When this position is reached movement may cease and the lining 35 exerts simple radial pressure upon the margin of the blank, as indicated

by the arrow in Fig. 5. This pressure may be exerted for any time interval desired, as provided in the travel of conveyor 1, or may be only momentary in the case of an extremely rapidly setting cement. After the cement 36 has formed a satisfactory bond, the lined ring 3 may be removed from the container either by stripping the same downwardly, as provided by stripper ring 18, or by removing the same upwardly. If desired, the removal may be effected by further movement of the sealing mechanism 4, particularly in the case of a fast setting cement.

The manner in which the lining 35 is clasped by the support 31 prevents the lining from executing a rolling or vortex ring movement and for this reason the necessary combined radial-stretching and axial-drawing effect upon the blank 33 is obtained. At the same time this effect is obtained through the deflection of flexible member 35, a matter which is of great importance 20 in the sealing of such containers as ordinary shell glass tumblers, as shown in Fig. 2. In such containers moderate variations in dimension and form occur and the deflection of member 35 satisfactorily accommodated the same without destruction to the tumblers, such as would occur in a case where rigid closing means are employed. In cases where the lining 35 is a ring of some other form than a hollow torus the carrier 31 need not fit so closely in order to prevent vortex ring 30 movement and other methods of carrying the ring may easily be devised which, nevertheless, will still be within the scope of this invention.

We desire it to be understood that this invention is not to be limited to any specific form or arrangement of parts except insofar as such limitations are specified in the claim.

What we claim as our invention is:

A machine for forming a closure for a container having an opening and side walls, which comprises a reciprocable member capable of forward and return movement, a carrier adapted to be moved by said reciprocable member during the forward movement thereof, a yieldable ring member having internal dimensions smaller than the external dimensions of the container mouth, said yieldable ring being clasped by said carrier to move therewith and yield therein without appreciable vortex ring movement, means to support a container in position to penetrate said yieldable ring when said reciprocable member, carrier and yieldable ring are carried through the forward movement of said reciprocable member and to retain said yieldable ring and carrier upon the return movement of the reciprocable member, and means for removing the carrier and yieldable ring from the container.

EDWARD J. STANEK,
ERICH MALO.
